LEG SPLINT

Application filed December 3, 1931. Serial No. 578,832.

This invention relates to surgical appliances and has special reference to a splint for the treatment of fractures of the lower limb such as fractures of the femur, tibia, fibula or os calcis either with skin traction or skeletal traction as with bone tongs, Steinmann pins or other apparatus of this nature.

More particularly the invention relates to a splint of the general type of what is known as a Böhler-Braun splint.

In the construction of this type of splint as heretofore manufactured a pair of metallic frames of trapezoidal shape are held in spaced relation by suitable cross members so that suitable fabric straps may be carried by the frames to support the thigh and leg portions of the limb. The thigh supporting portion is arranged to incline upwardly from the base part of the splint, the lower members of the frames carrying the lower extremities of the inclined portions. At the foot portion of the splint there is an arch for the suspension of the patient's foot in certain cases of fracture. Suitable means are provided for supporting pulleys on this arch frame and on an extension of the tops of the side frames.

Splints of this type heretofore manufactured, have lacked adjustability to fit the various positions necessary for various types of fractures.

One defect found in former splints of this kind is that no provision is made either for variations in the lengths of the upper or thigh portions of different limbs nor is any provision made for adjusting the angularity of the inclined thigh portion of the splint.

In the present invention, however, the femur supporting section is adjustable to a wide variation of angle from the horizontal and this adjustment is accomplished by a simple screw device which holds the femur supporting portion in any desired position. Furthermore, this adjustment is of such character that the femur portion of the splint is adjustable independently of the remainder of the splint whereby the canvas supporting straps or slings can be brought snugly into contact with the posterior aspect of the thigh. This adjustment can only be attained

in the usual form of splint by blocking up the rear end of the splint by improvised means, such as boards or books.

Also the side rods of this adjustable femur section are, in the present invention, adjustable in length to accommodate different lengths of femurs. In this connection the uppermost canvas sling is cut on the bias with the wider end on the outside of the femur to give more support to that side, the wide end being shifted from one side to the other according to whether the splint is to be used on the right or left leg.

A further object attained by the present invention is that the femur section of the splint is so supported and arranged that the use of a bedpan is not interfered with since the lower frame parts terminate beneath the knee supporting portion of the splint.

A further object attained by this invention is due to the fact that the vertical rods are extensible so that the femur and leg portions of the splint may be bodily adjusted for height, this adjustment for height increasing the range of angular adjustment of the femur supporting portion of the splint and also aiding in the accommodation of various lengths of femurs.

It is desirable that traction be capable of being exerted on the broken bone in exactly the line necessary to maintain the broken sections in natural alignment. To accomplish this object the present invention is provided with arches supported from the upper bars of the frames and adjustable both longitudinally of these bars and for height and these arches carry pulleys over which the traction cords may pass. By this adjustment of the pulleys the surgeon is enabled to produce traction in exactly the direction desired regardless of the angle of the same.

At times, in certain fractures of the leg and ankle, it is desirable to apply traction to the foot or ankle at a particular angle. This object is accomplished by arranging the nose or front portion of the splint and is also angularly adjustable by means similar to those employed for the femur portion. This nose carries the usual wheels for supporting the traction cords. In addition this nose por-

tion is extensible so that the wheels may be positioned beyond the foot of the bed a sufficient distance to prevent the weights used in traction from striking against the bed frame.

With the above and other objects and advantages in view the invention consists in general of certain novel details of construction and combinations of parts illustrated in the accompanying drawings, fully described in detail and specifically claimed.

In the accompanying drawings like characters of reference indicate like parts in the several views, and:

Figure 1 is a perspective view of the splint in use.

Figure 2 is a vertical section on the longitudinal median plane of the splint, the section showing particularly the femur supporting portion of the frame.

Figure 3 is a view similar to Figure 2 but showing a portion of the front or nose end of the device.

In the form of the invention here disclosed there is provided a pair of lower side frame members 10 which are held in laterally spaced relation by cross members 11. From these side members 10, adjacent their ends, rise the vertical posts 12 which are threaded and have their upper parts slidably received in vertical tubular upper post sections 13. Butterfly adjusting nuts 14 are mounted on the lower posts 12 so that the height of the posts may be regulated. The upper ends of the sections 13 at each side are connected by an upper side bar 15 and these side bars extend beyond the posts at each end. At the thigh or femur end of each bar 15 is a pivot 16 and on these pivots are connected the side members 17 of the femur support, these side members being connected by an inverted arch like cross-bar 18. Also the rear tubular members 13 are connected by a cross bar 19. On this bar 19 is mounted a sleeve 20 to which is welded or otherwise fixed a second sleeve 21 which extends at right angles to the sleeve 20. On the yoke or cross member 18 is mounted a swivel 22 to which is pivoted the rear end of a threaded adjusting bar 23 and on this bar is mounted a butterfly nut 24. As can be clearly seen from Figure 2 the adjustment of this nut, which bears on the rear end of the sleeve 21, controls the angular position of the femur supporting frame. It will be noted that the members 17 are tubular and internally threaded to receive the threaded femur frame extension rods 25. By this arrangement the femur supporting frame can be lengthened or shortened as the case may require.

Similarly, at the front ends of the frame members 15 are pivots 26 to which are connected the forward ends of frame extension members 27 which are connected by a cross bar 28. The upper members 13 at this end are connected by a cross bar 29 on which is a sleeve 30 carrying a cross sleeve 31. A swivel

32 is mounted on the cross member 28 and pivotally supports the front end of a threaded adjusting rod 33 which passes through the sleeve 31 and on which is mounted a butterfly nut 34 which serves the same purpose for the front frame as the nut 24 at the rear. Slidably mounted on the members 27 is the extension nose 35 and this extension is held in adjusted position by the thumb screw 36. Pulleys 37 are carried by this nose.

Clamps 38 are slidably mounted on the frame members or bars 15 and in these clamps are mounted the legs of arches 39, each clamp having a single thumb screw 40 by which the clamp is screwed in adjusted relation on the member 15 and the arch leg is simultaneously secured in vertical adjustment in the clamp. The arches 39 carry at their tops the pulley wheels 41. Sling straps 42 connect the members 15 and also connect the members 17 and 25.

In Figure 1 the splint is shown as being used with a patient having fractures of the right femur and right tibia, for instance. The femur supporting frame is adjusted in length to suit the upper limb and to the angle desired by the attendant surgeon, the vertical posts being adjusted in height to allow such adjustments without bringing the ends of the members 25 into contact with the bed. The rear arch 39 is adjusted on the rods 15 and for height to bring the pulley 41 carried by it to proper position and is there secured. Traction straps S are adhesively affixed to the lower part of the thigh and are carried through a stirrup or loop L to which is connected a cord C which extends over the pulley 41 and the front pulley 37, the extensible nose frame being adjusted for this purpose. For the lower leg traction is exerted by an adhesive strap S' extending through the stirrup L' to which is connected a cord running over the rear pulley 37. The front arch 39 may be used to support the toe portion of the foot as shown in Figure 1. Weights W carried by the cords exert the proper amount of traction.

While one arrangement of the parts is shown in Figure 1 it is obvious that the wide adjustability of the splint enables it to be used to great advantage in practically all fractures of the lower limb and it is to be understood that the utility of the splint is by no means confined to the particular example shown in Figure 1.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired

to include all such as properly come within the scope claimed.

Having thus described the invention, what is claimed as new, is:

5. 1. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 70
10. 2. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, and means connecting the extension frame with the upper member of the adjacent posts to hold the extension frame in angularly adjusted position. 75
15. 3. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 80
20. 4. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 85
25. 5. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 90
30. 6. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position, a second extension frame 95
35. hinged to the longitudinal bars at the opposite end of the splint to swing to desired vertical angles, and means connecting the second frame with the upper member of the adjacent posts to hold the second frame in adjusted position, one of said extension frames being provided with sling straps and the other with traction cord wheels, clamps slidably mounted on said bars, an arch having legs extending through said clamps for vertical adjustment therein, a traction cord pulley carried by said arch, and means to secure the clamps in adjusted positions on the bars and the arch in adjusted position in the clamps. 100
40. 7. In a splint of the kind described, a main frame including upper and lower longitudinal frame bars, said frame also including extensibly connected upper and lower post members rigidly fixed respectively to the upper and lower longitudinal members; extension frame members pivoted to the upper frame bars at one end of the splint for adjustment to desired vertical angles, means carried by the adjacent upper post members of the main frame and connected to the extension frame members for supporting the extension frame members in angular adjusted position, clamps slidably mounted on said upper bars, an arch having legs extending through said clamps for vertical adjustment therein, a traction cord pulley carried by said arch, and means to secure the clamps in adjusted positions on the upper bars and the arch in adjusted position in the clamps. 105
45. 8. In a splint of the kind described, a main frame including upper and lower longitudinal frame bars, said frame also including extensibly connected upper and lower post members rigidly fixed respectively to the upper and lower longitudinal members; extension frame members pivoted to the upper frame bars at one end of the splint for adjustment to desired vertical angles, means carried by the adjacent upper post members of the main frame and connected to the extension frame members for supporting the extension frame members in angular adjusted position, clamps slidably mounted on said upper bars, an arch having legs extending through said clamps for vertical adjustment therein, a traction cord pulley carried by said arch, and means to secure the clamps in adjusted positions on the upper bars and the arch in adjusted position in the clamps. 110
50. 9. In a splint of the kind described, a main frame including upper and lower longitudinal frame bars, said frame also including extensibly connected upper and lower post members rigidly fixed respectively to the upper and lower longitudinal members; extension frame members pivoted to the upper frame bars at one end of the splint for adjustment to desired vertical angles, means carried by the adjacent upper post members of the main frame and connected to the extension frame members for supporting the extension frame members in angular adjusted position, clamps slidably mounted on said upper bars, an arch having legs extending through said clamps for vertical adjustment therein, a traction cord pulley carried by said arch, and means to secure the clamps in adjusted positions on the upper bars and the arch in adjusted position in the clamps. 115
55. 10. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 120
60. 11. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 125
65. 12. In a splint of the kind described, a main frame including vertically extensible posts consisting each of an upper and a lower member movable relatively one to the other and means for holding the posts in extensibly adjusted positions, said frame also including upper longitudinal frame bars each connecting the upper members of a pair of the posts to form one side of the splint, an extension frame hinged to the longitudinal bars at one end of the splint to swing to desired vertical angles, means connecting the extension frame with the upper member of the adjacent posts to hold the extension frame in angularly adjusted position. 130

In testimony whereof I affix my signature.

JOE J. ETTINGER.
